WICKET FOR RIVER DAMS

James C. Travilla, University City, Mo., assignor to General Steel Castings Corporation, Granite City, Ill., a corporation of Delaware

Application August 21, 1952, Serial No. 305,524

6 Claims. (Cl. 61—27)

This invention relates to river dams comprising a plurality of movable wickets and, more particularly, to the construction of the individual wickets.

One wicket type river dam comprises a plurality of wickets mounted side by side upon a foundation on the river bed. Each wicket is adapted to swing from a lowered position in which it rests upon the dam foundation substantially throughout its length into a raised position for creating, during low river stages, a pool on the upstream side which will float vessels to be passed through locks at one side of the river.

Heretofore, the individual wicket has been built of a plurality of wood timbers bolted together with metal binders and trim members, and having metal hinges secured thereto. In use, these timbers become water soaked when resting upon the foundation on the river bed and rot when raised and subjected to the elements. It is customary to use wooden strips or "needles" to fill the spaces between adjacent wickets, but warping and twisting of the timbers result in their disalignment and irregular spaces between them. The timbers are subjected to jarring impacts when the wickets are released for dropping into resting position upon the foundation, and such impacts will loosen the metal binders and trim.

Hence, wickets of the usual wooden timber construction require extensive maintenance with frequent replacement of wickets and needles. Furthermore, the nature of the construction of these wickets inherently causes production thereof to be costly in that extensive handling is involved with the application of metal binders and trim members to the timbers.

It is a primary object of the present invention to provide an all-metal wicket which is formed substantially as a single unit entirely by ordinary foundry practice, i. e., by green sand molding.

It is a further object to provide a wicket of rigid, strong structure which will maintain its contour during extensive use with minimum maintenance, and which will resist tendencies to lose alignment with the adjacent wickets, thereby obviating the use of varying interposed needles and the replacement of the needles.

It is an additional object to provide a cast metal wicket which is resistant to corrosion and which is so designed as to be substantially free of shrinkage strains and the like.

It is a further object to provide a wicket of the character stated which will be durable and reliable in usage and which may be most economically manufactured.

These and other detailed objects, as will appear from the description below, are attained by the structure illustrated in the accompanying drawings (three sheets) in which:

Figure 1 is a perspective view showing a portion of a movable wicket-type river dam incorporating wickets constructed in accordance with and embodying the present invention and also indicating a barge for operating the wickets.

Figures 2, 3, 4, and 5 diagrammatically illustrate successive stages in the raising and lowering of a wicket.

Figure 6 is a plan view of the normally upstream face or top of a single wicket.

Figure 7 is a side elevation of the wicket.

Figure 8 is a plan view of the normally downstream face or bottom of the wicket.

Figure 9 is an end view of the normally forward or upstream end of the wicket.

Figure 10 is an end view of the normally rear or downstream end of the wicket.

Figure 11 is a longitudinal vertical section on line 11—11 of Figure 6 with portions broken away to enable the drawing to be made to a larger scale.

Figure 12 is a transverse section on line 12—12 of Figure 6.

2

Figure 13 is a transverse section on line 13—13 of Figure 6.

Figure 14 is a detail horizontal section on line 14—14 of Figure 13.

Figure 15 is a detail longitudinal vertical section on line 15—15 of Figure 6.

In Figure 1, A designates a portion of a movable wicket-type river dam comprising a masonry foundation 1 constructed on a river bed 2. A plurality of wickets 3 are mounted for swinging about a horizontal axis between lowered or rest position upon foundation 1 (Figure 2) and elevated or operative position (Figure 4) to provide a barrier during low river stages for developing pools upon the upstream side. Secured to the underside or downstream face of each wicket 3 intermediate its ends are wicket boxes 5, one near each side of the wicket. Boxes 5 journal a shaft 4 which mounts a sleeve 6 secured to the forward or upstream end of a prop 7, the rearward or downstream end of which is free and extends beyond the downstream end of the wicket when the wicket is lowered. At opposite ends of sleeve 6 are the sleeve-like, normally upper ends of a pair of braces 8, having their sleeve-like lower or upstream ends receiving a rod 9 mounted upon foundation 1 and extending transversely of the stream. The ends of the wicket are provided with short cross bars 12, 13, respectively (Figures 9, 10, 11) for engagement by a hook arm H mounted on a barge B.

The operation of raising and lowering a wicket 3 is diagrammatically illustrated in Figures 2—5, inclusive. To elevate wicket 3 from a position of rest (Figure 2), hook arm H is engaged about the wicket forward cross bar 12 and is then raised and moved upstream to lift the wicket forward end 10, the force of the stream holding the wicket substantially horizontal (Figure 3), and braces 8 are swung into vertical position. As the forward end of prop 7 is raised, its free rear end is received within a notch 14 in foundation 1, thereby holding wicket 3 against movement downstream. Hook arm H is then depressed to rock the wicket forward end 10 downwardly and downstream about shaft 4, which is stably positioned by the upper ends of braces 8 and prop 7. When wicket 3 has been swung sufficiently to permit the stream to strike its forward face, the stream swings the wicket forward end 10 into abutment with a sill 15 on foundation 1 (Figure 4). In this position, wicket 3 is fully raised and supported for damming purposes.

To return the wicket to lowered position, hook arm H is engaged with rear cross bar 13, which is now uppermost, and the wicket rear end 11 is pulled upstream pivoting about the wicket forward end 10 on sill 15 and moving prop 7 out of notch 14 (Figure 5). The lower end of prop 7 is moved to the right by a foundation cam ledge L (Figure 1). Thereupon hook arm H is moved downstream and swings the wicket into substantially horizontal position with the face thereof parallel with the stream. Hook arm H is then released and the wicket swings downwardly into lowered position (Figure 2).

The wicket forming the present invention is of all metal construction, preferably consisting of a one piece metal casting shaped to provide adequate strength with minimum amount of metal and in a form which may be produced with a minimum amount of cores and machining. In plan view (Figure 6) the wicket corresponds in length and width to wooden or composite wickets previously used. In transverse and longitudinal section, the wicket has contours substantially different from wickets previously used.

The wicket embodies a web structure substantially continuous from end to end and from side to side of the wicket with portions offset from each other upwardly and downwardly of the wicket to form a series of U-like sections or deep corrugations extending substantially from end to end of the wicket and providing longitudinal depressions in the upwardly facing and downwardly facing web portions to form a rigid structure between the ends of the wicket. (Figure 12.)

The corrugations or depressions include a downwardly opening central section 17, upwardly opening intermediate sections 18, and downwardly opening side sections 19. Web portions 20 and 21, respectively, of sections

3

17 and 19 form the upper face or top of the wicket. Web portions 22 of sections 18 form the lower face or bottom of the wicket. Substantially upright web portions 25, 26, and 27 form the sides of the sections and rigidify the wicket between its top and bottom web portions.

Near the downstream or right hand end 11 of the wicket, bottom web portions 22 are inclined upwardly longitudinally of the wicket at 24 and merge with upper web portions 20 and 21 to form a substantially continuous top face 28 extending from side to side of the wicket (Figure 6) except at the center where a pocket 29 is formed to receive cross bar 13, which is projected through web portions 25 and welded in place (Figure 10).

Near the upstream or left hand end 10 of the wicket, the central upper web portion 20 is inclined downwardly longitudinally of the wicket at 30 and merges with web portions 22 to form a substantially continuous lower face 31, extending from side to side of the wicket (Figure 8). Abreast of inclined portion 30, the upright web portions 26 converge at 32 and then extend forwardly, cooperating with portion 30 to form a pocket 33 to receive cross bar 12, which is projected through webs 26 and welded in place (Figure 9).

Upright end web portions 34, 35 at the forward and rear ends, respectively, of the wicket extend from side to side of the wicket, except for the pockets 33 and 29, and merge with web portions 20, 21, 22, and 27 and with web portions 31 and 28 respectively form box-like end structures further rigidifying the wicket.

The sides of the U sections or deep corrugated converge towards their top and bottom webs so as to facilitate molding operations and the corners between webs extending in different directions are rounded for the same general purpose.

Intermediate the ends of the wicket, the central corrugation 17 is widened, and the side corrugations 18 are correspondingly narrowed, and flanges 36 project from the bottom of sections 18 and separately formed wicket boxes 5 are applied to flanges 36. Vertical ribs 37 extend transversely of the wicket from side to side above flanges 36 to which the wicket boxes are applied and rigidify the wicket transversely of its depth (Figure 13).

Between wicket box mounting flanges 36 and the wicket rear end 11, flanges 38 project from the bottom of sections 18 and separately formed buffer blocks 39, preferably of wood, may be secured to flanges 38 to cushion the impact between the wicket and the foundation when the wicket is lowered, and to support the wicket in such position (Figure 1). Transverse upright ribs 40 merge with flanges 38 and the adjacent longitudinally extending web portions to further rigidify the wicket transversely of its length.

Relatively short upright reinforcing ribs 41 extend inwardly from rear end web portion 35 far enough to reinforce the adjacent part of the wicket which receives the hook arm H.

The wicket is an integrated, unitary casting, preferably of steel, which is designed for economical production substantially by green sand molding. The inclination of the sides of the surfaces and the web portions, between the top and bottom web portions, and the rounded corners permit the casting to be readily parted from its mold, as well as to tend to eliminate the possibility of the development of shrinkage strains. Only a small amount of coring is required as at flanges 36, 38 and at the holes for pins 12, 13.

In operation, the wickets provide a rigid, strong structure which is resistant to weaving or bending because of the rigidity inherent therein, as a result of the corrugated form and the reinforcing ribs.

Accordingly, the wickets will better maintain their alignment and there will be no deterioration along their margins and this will avoid excessive variations in the intervening "needles" used to fill spaces between adjacent wickets, as indicated in Figure 12. Such needles may take the form of wood strips N or metal pipes N'.

The details of construction may be varied without departing from the spirit of the invention and the exclusive use of those modifications coming within the scope of the claims is contemplated.

What is claimed is:

1. A wicket of the class described comprising an elongated casting having transversely spaced top web portions, transversely spaced bottom web portions, said top and

85

4

bottom web portions being offset from each other transversely of the general plane of the wicket and web portions extending between said top and bottom portions and merging therewith to form a series of corrugations extending lengthwise of the wicket and corresponding in depth to the depth of the wicket, there being flanges of restricted length on at least one of said bottom web portions spaced below the level of an adjacent top web portion and projecting laterally beyond the edge thereof to form a mounting bracket for a wicket accessory.

2. A wicket as described in claim 1 which includes a flange on at least one of said bottom web portions projecting laterally from and spaced beneath an adjacent top web portion to form with said bottom web portion a mounting bracket for a wicket accessory, there being a rib extending upwardly and downwardly from said bottom and top web portions respectively and extending between said flange and the adjacent upwardly and downwardly extending web portion to brace said bracket from the remainder of the wicket structure.

3. A cast metal wicket for a river dam comprising an elongated body having upper and lower faces, spaced apart, said upper face having a pair of longitudinally depressed on opposite sides of the longitudinal axis of said body for dividing said upper face into a central web portion and a pair of lateral web portions, said depressions terminating spacedly from the normally downstream end of said body and converging toward each other for a confluence spacedly from the normally upstream end of said body, said upper face further having an axial depression opening at the upstream end of said body and being in communication at its other end with said longitudinal depressions coincident with their point of confluence, and a hook-engaging bar extending transversely across said axial depression adjacent the upstream end of said body in spaced relation to the base of said axial depression.

4. A cast metal wicket for a river dam comprising an elongated body having upper and lower faces, said upper face having a pair of longitudinal depressions on opposite sides of the longitudinal axis of said body for dividing said upper face into a central web portion and a pair of lateral web portions, said upstream face having an upwardly opening recess at the upstream end of said body and having an upwardly opening recess adjacent the downstream end of said body, and a hook-engaging bar within and extending transversely across each of said recesses in spaced relation to the bottoms thereof.

5. A cast metal wicket for a river dam comprising an elongated body having upper and lower faces spaced apart, said upper facing having a pair of longitudinal depressions on opposite sides of the longitudinal axis of said body and dividing said upper face into a central web portions, in planar alignment with each other, said lower face having three longitudinal depressions formed therein immediately below the central and lateral web portions of the upper face and forming a pair of web portions disposed on either side of the longitudinal axis of the body and being in planar alignment with each other, whereby said upper face web portions and said lower face web portions are at the top and bottom of the wicket, respectively.

6. A cast metal wicket of the type described in claim 3 wherein the central and lateral web portions of the upper face are in planar alignment, said central web portion being inclined downwardly at its upstream end for merging into the axial depression, said lower face having three longitudinal depressions formed therein dividing said face into a pair of elongated web portions which merge at their upstream end with the base of the axial depression.
